UNITED STATES PATENT OFFICE.

CLARENCE H. WILLIAMSON, OF ALTOONA, PENNSYLVANIA.

FASTENING DEVICE.

1,247,772.

Specification of Letters Patent. Patented Nov. 27, 1917.

Application filed April 10, 1916. Serial No. 90,097.

To all whom it may concern:

Be it known that I, CLARENCE H. WILLIAMSON, a citizen of the United States, residing at Altoona, in the county of Blair and State of Pennsylvania, have invented 5 certain new and useful Improvements in Fastening Devices; and I do hereby declare the following to be a full, clear, and exact description of the invention, such as will 10 enable others skilled in the art to which it appertains to make and use the same.

While my invention is primarily designed to afford efficient fastening means which are especially suitable for maintaining the moving 15 parts of a key-connected draft rigging in proper assembled position under the peculiar conditions of service to which draft riggings for railway cars are subjected, it will be apparent that such fastening means 20 are also useful in many other relations.

The main feature of my invention, generally stated, consists in providing a detachable head for a key or bolt, said parts constituting a fastening device and being adapted 25 to have interlocking engagement preventing the removal or detachment of said head except upon successive turning movements of the latter about independent axes.

There are other features of my invention, 30 relating to the form and mode of coöperation of the parts of the fastening device, all as will hereinafter appear and be particularly pointed out in the claims.

In the drawings illustrating my invention, 35 the scope whereof will appear from the claims:

Figure 1 is a side elevation of a draft rigging and a portion of the car underframe with which the draft rigging coöperates.

40 Fig. 2 is a plan view of a portion of a fastening device embodying my invention, the detachable head being shown in full lines in locked position, and being shown in dotted lines in a position which it assumes when 45 being disengaged from the body portion of the key or bolt.

Fig. 3 is a transverse section on the line 3—3, Fig. 2, the detachable head being in locked position and the relation of a coupler 50 butt to such a fastening means being shown in dotted lines.

Fig. 4 is an end view of the fastening device, the detachable head thereof being shown in one of the positions which it assumes when being detached from the key or bolt.

Although the invention is advantageously

applicable to key-connected draft riggings generally, I have, for purposes of explanation, illustrated it as applied to a draft rigging mechanism of the character shown and described in the patent to I. O. Wright *et al.*, No. 841,757, issued January 22, 1907.

In the drawings the key or bolt member of the fastening device is indicated by the 60 numeral 1, and 2 is the detachable head. The key is preferably provided at one end with an integral head 3 and near its opposite end it is fashioned with oppositely disposed slots or notches 5 which thus reduce the 65 cross-sectional area of the key 1. These notches are adapted to receive portions of the detachable head 2, which is preferably formed as a completely closed loop or ring having upper and lower bars or walls 6 and 75 7, respectively, and end or side walls or bars 8 and 9, respectively.

The inner face of the side wall 8 is preferably provided, adjacent the upper wall 6, with a beveled portion 10, which normally 80 lies in one of the slots 5 and which permits the detachable head 2 to be swung upwardly into the position shown in Fig. 4, and then rotated outwardly as indicated by dotted lines in Fig. 2 to effect its detachment from 85 the key 1. Below this beveled portion 10, the inner face of the side wall may be provided with an inwardly extending shoulder 11 adapted when the head is in locked position to underlie a portion of the key or 90 bolt. The opposite side 9 of the detachable head is provided with an outwardly curved or recessed portion 12, adjacent the lower wall 7, for a purpose to be hereinafter described.

95 The end portion of the bolt or key 1, adjacent the notches 5 is provided with beveled sides 4, the inclination of the beveled faces being such that each face will lie within a circle struck from the inner edge of the oppositely disposed notch, with a radius equal to the maximum diameter of the opening formed in the detachable head 2.

100 The numeral 13 designates the coupler of the draft rigging, 14 and 15 the followers, 105 and 16 the springs. These movable parts of the draft rigging are maintained in proper position between the draft or center sills 17 by means of the fastening device hereinbefore referred to. The end sill is 110 indicated by the numeral 17^a, and 18 and 19 are respectively the striking casting and the coupler carry-iron.

Owing to the constant movement of the

different transversely extending key portions of the fastening means under normal conditions of operation of the draft rigging, and to the tendency of the key portions to move laterally when the cars are passing around curves, it becomes necessary to provide means to coöperate with the key portions to retain the same in proper assembled relation. The means which will satisfactorily accomplish this purpose must of necessity, to be practicable, present a large wearing area, and also must permit the side movement of the key portions, and must be readily detachable to enable the key portions to be readily withdrawn in order to make repairs to the draft gear parts, and while the detachability of the said means is of paramount importance it is equally essential that the means be so connected to the key portions as to absolutely prevent the accidental removal of the said means.

The detachable head 2 of the fastening means fully meets all of the requirements set forth above, in that it presents a large wearing surface to the outer face of the sills and is interlocked with the key or bolt so as to positively permit the lateral or transverse movement of the key or bolt. To remove the head 2 the same is first rotated on the corner adjacent the portion 10 so as to place the curved portion 12 in line with edge of the key or bolt, as shown in Fig. 4, and then the head is again rotated on the portion 10 as an axis and in a direction at right angles to the first rotation, until the side 9 clears the end of the key or bolt, after which the side 8 may be slipped out of the notch or slot 5.

The opening in the head 2 is non-circular and may be, and preferably is, unsymmetrical, and the maximum diameter thereof is less than the diameter of the key or bolt. The formation of the detachable head absolutely prevents the accidental removal of the same, since any force tending to raise the head lineally in a vertical direction would, owing to the shoulder 11, cause the side wall 9 to bind against the base of the notch 5 with which the same is engaged, and thus prevent the rising of the head. Moreover, even should the head be jarred into the position illustrated in Fig. 4 it would still be interlocked with the key and only disengageable therefrom by an outwardly directed force acting on the inner face of the side wall 9. The detachable head is normally maintained in interlocked relation with the key by the action of gravity.

Having now described my invention, what I claim and desire to secure by Letters Patent is:

1. The combination of a key and a rigid

detachable head having interlocking engagement with said key, said key having intermediate of its ends a portion of reduced cross-section, and said detachable head having a non-circular opening therein whose greatest width is less than the maximum transverse width of the key. 65

2. The combination with a key having intermediate of its ends a portion of reduced cross-section and having a tapered end, of a rigid head adapted to be detachably mounted on said key, said key and said head having interlocking engagement, and said head having an unsymmetrical opening therein whose greatest width is less than the maximum transverse width of the key. 70

3. The combination with a key having intermediate of its ends a portion of reduced cross section formed by notches, of a head detachably connected to said key at said portion, the head having an opening therein through which said key extends, the minimum diameter of said opening measured between two of its sides being greater than the reduced width of the key, the maximum diameter of said opening between the same two sides being less than the maximum width of said key and greater than the width of said key 90 less the depth of one of the said notches. 85

4. The combination with a key, of a detachable head having interlocking engagement therewith, said head having therein an unsymmetrical opening through which the end of said key is adapted to project, one of the end walls of said opening having a recess therein corresponding to and normally spaced from the adjacent side of the said key when said head is in locking position. 100

5. The combination of a key and a detachable head therefor, said key having a shouldered portion adapted to interlockingly engage said head and serving as means for preventing the disengagement of said head except upon successive turning movements of said head about different axes. 105

6. The combination of a key and an elongated detachable head therefor, said key having a shouldered portion adapted to interlockingly engage said head, said head having an elongated opening therein through which said key extends, portions of the said key being adapted to engage the end walls of said opening to prevent the movement of said head in the direction of the length of the said opening, said head being detachable from said key by a rotary movement of the head with respect to the key. 110 115 120

In testimony whereof I affix my signature.

CLARENCE H. WILLIAMSON.
